CLEANING DEVICE

Raymond A. Kelly and Winfield F. Raddon,
Salt Lake City, Utah

Application May 22, 1940, Serial No. 336,608

6 Claims. (Cl. 15—104)

This invention relates to an improved cleaning device, and more particularly, a cleaning device which is advantageously used manually in the cleaning of such items as textile fabrics.

The principal objects of the invention are to provide:

First.—A device that is simple, efficient and inexpensive.

Second.—A device that not only loosens dust and dirt, but which collects at least the greater part of the same for convenient disposal.

Third.—A device which improves a textile surface by fluffing and conditioning the fibers thereof.

In general, the device comprises a plurality of 15 depending riffles suitably supported and spaced apart from one another, the individual riffles being fluted or corrugated across the length thereof, thus defining a series of passages through which dust or dirt particles are carried upwardly and 20 deposited in appropriately recessed cells.

In using the device, it is placed in contact with, and given a brushlike motion over, the surface of a fabric to be cleaned, the lower edges of the riffles serving to vigorously knead and otherwise manipulate the nap or thread of the fabric. This serves to loosen the dust or dirt particles and to bring them to the surface, whereupon the particles are largely picked up and retained within the structure of the device. At suitable intervals, the accumulated dust or dirt is emptied and disposed of as desired.

In the drawing, which illustrates one embodiment of the invention:

Fig. 1 represents a top plan;

Fig. 2, a longitudinal section taken on the line 2—2 in Fig. 1;

Fig. 3, a bottom plan;

Fig. 4, a vertical cross-section taken on the line 4—4 in Fig. 3;

Fig. 5, a fragmentary cross-section similar to a portion of Fig. 4, but showing riffles of another construction;

Fig. 6, a fragmentary cross-section showing riffles of still another construction; and

Fig. 7, a section taken on the line 7—7 in Fig. 6.

Referring to the drawing, the numeral 20 indicates a back or housing into which is fitted an easily removable rifle structure 21. The particular configuration of both the housing and the rifle structure and the material of which these are made, may be varied within wide limits. For example, the present showing contemplates these structures as being made of any of the numerous plastic compounds suitable for the purpose. If desired, the design may be adapted to the use of various other materials, such as wood or metal.

The back or housing may have any desired configuration suited to an indefinite number and variety of uses. In the present example, one end

is pointed, as indicated at 24 in Figs. 1 and 3, so that the device can be nosed into restricted spaces such as the re-entrant angular corners of upholstered furniture, a good example being chairs or davenport's of the overstuffed type.

The back or housing 20 may have a depending wall 25 following its contour, and the wall be internally grooved as indicated at 26, to receive a removable rifle structure.

The rifle structure may consist of a plurality of individual riffles 27 upwardly fluted or corrugated as clearly indicated in Fig. 3. The riffles may extend longitudinally of the device and may advantageously be substantially parallel to one another. In the present instance, the individual riffles are supposed to be integral with a frame 28 and with an end piece 29, the frame being fitted to slide, drawerlike, in the groove 26. The frame and riffles may be suitably stiffened, for example, by means of the cross connections 30.

It is desirable that the rifle structure should normally be held in the assembled form in a manner to resist any tendency to become disassociated in normal use. This can be accomplished in various ways, for example, by providing sufficient frictional resistance between the frame 28 and the contacting surfaces of the groove 26.

In a preferred construction of the device, the individual riffles 27, in cross-section, are advantageously of hollow V-shape as clearly shown in Fig. 4, these riffles being disposed in transversely spaced relation to one another. The spaces 31 are at least partially defined by the extremities of the V-legs and therefore extend longitudinally of the structure. A chamber 32 is advantageously provided above the extremities of the V-legs and below the inner surface 34 of the back, for a purpose presently to be described.

For convenience in holding the device with the fingers of one hand, grooves 35 may be provided along the top edges of the housing as is customary on ordinary brushes.

In using the device, the vertices of the V-riffles, which may be slightly rounded as indicated in Fig. 4, are brought into contact with the surface to be cleaned, and the entire structure moved back and forth in brushlike strokes across the surface. The most effective cleaning strokes are transverse because not only are the constituents of a fabric 50 vigorously agitated, but at the same time, there is a pronounced tendency to create a partial vacuum back of each moving riffle, and this tendency produces a suction and a resultant inrush of air which lifts the dust or dirt particles up through 55 the space between any two of the riffles and through the ports 36 into the chamber 32, from where the particles drop into the V-shaped recesses 36 of the riffles.

The carrying capacity of the dirt-laden air currents is increased by a Venturi effect exerted be-

cause of the upwardly converging passages between consecutive riffles. The fluting of the riffle sides forms spaced, upwardly directed conduits and divides the up-rushing air into separate streams which further enhance the dirt-carrying capacity of the air streams.

Strokes in the direction of the arrow 37, Fig. 4, have a tendency to create the vacuum immediately in back and on the far side of the riffles, thereby tending to cause the induced air-currents to follow approximately the upwardly directed arrows. Strokes whose direction is counter to the arrow 37, tend to induce corresponding air-currents on the opposite side of the riffles. Thus, as the device is briskly moved back and forth, opposing air currents are continually meeting and neutralizing one another in the chamber 32, which causes the dirt particles to drop as aforesaid into the recesses or cells 36 of the riffles.

The alternate, dotted position 29a, of the end piece 29, Fig. 3, indicates the operation of pulling out the riffle structure 21 for the purpose of emptying the accumulated dirt.

Advantageously, the depending wall 25 and end wall 29 may have the lower edge thereof, at a level sufficiently high above the lower level of the riffle tips, as indicated for example, at 38 in Fig. 4, to cause the riffle tips to sink into a fabric.

In Fig. 5, the riffles 39 show a V-shaped exterior configuration but are solid instead of being hollow as are those in Fig. 4. In both these examples, however, the converging spaces 40 in the case of Fig. 4, and the converging spaces 41 in the case of Fig. 5, are of substantially inverted V-shaped definition, thus maintaining the stated Venturi effect, in operation. The efficiency of the present device is attributed largely to the maximum compacting of the air currents as they flow through the conduits formed by the flutes which converge in Fig. 4.

In Fig. 5, the sides of the V-riffles 39 are designed to be substantially plane, as an alternate construction. In this case the beneficial action of the flute conduits may not be obtained, but a considerable compacting action is still exerted upon the air streams which finally emerge through the ports 42 and are projected into the chamber 43.

The ports 31 in Figs. 3 and 4, and the ports 42 in Fig. 5, virtually form nozzles which extend the major linear dimensions of the respective riffles. In some cases, the V-shaped riffles of Fig. 5 may be used without the chamber 43, thereby bringing about a somewhat different operative action from that previously described.

In Figs. 6 and 7 are shown depending riffles 45 which are substantially uniform in thickness from top to bottom, but at the same time are fluted across their length. In this case, the spaces 46 between successive riffles do not afford the benefits of convergence, but they do have the advantages that are derived from the fluted feature.

Having fully described our invention, what we claim is:

1. A cleaning device, including in combination, a plurality of depending riffles spaced apart longitudinally one from another, the said riffles being provided with flutes having peaks and valleys extending transversely of the said riffles, the distance from peak to peak and valley to valley being equal approximately to the distance from riffle to riffle, and means disposed to support the riffles in the said spaced relation.

2. A cleaning device, including in combination, a plurality of depending riffles having a V-shaped cross-section, the said riffles being spaced apart, one from another longitudinally, so as to form inverted, substantially V-shaped spaces between consecutive riffles, a plurality of flutes having peaks and valleys disposed in the faces of the V-legs and extending transversely of the longitudinal dimension thereof, the distance from peak to peak and valley to valley being approximately equal to the distance from vertex to vertex of the V-legs, and means disposed to support the riffles in the said spaced relation.

3. A cleaning device, including in combination, a plurality of depending riffles having a V-shaped cross-section and a longitudinal dimension, the said riffles being spaced apart laterally one from another, along the longitudinal linear dimension thereof so as to at least partially define ports between the adjacent V-leg extremities of consecutive riffles, flutes formed in the V-legs, said flutes having peaks and valley disposed transversely of the V-legs, a supporting structure disposed to hold the riffles in the said spaced relation, and a chambered structure above, and in communication with the said ports.

4. A cleaning device, including in combination, a plurality of depending riffles extending along a longitudinal dimension and having a recessed, V-shaped cross-section, the said riffles being spaced apart laterally one from another along the major linear dimension thereof so as to at least partially define ports between the adjacent V-leg extremities of consecutive riffles, each of the longitudinal faces of the legs of the V having flutes, the peaks and valleys of which are disposed transversely of the said longitudinal dimension, supports for the riffles, and a chambered structure above and in communication with the said ports and with the recesses of the said V-shaped riffles.

5. A cleaning device, including in combination, a plurality of hollow, depending riffles each provided with a ridge and wings springing away from the ridge to form substantially a V-shaped cross-section, the said riffles being spaced apart laterally one from another along the major linear dimension while a rifle wing is fluted transversely of the ridge of the rifle; and a supporting structure disposed to hold the said riffles operatively in the said spaced relation.

6. A cleaning device, including in combination, a housing having a back, a curtain wall depending from the back and at least partially coextensive with the outline thereof, a frame separably fitted into the housing, and a plurality of riffles depending from the said frame, the said riffles being spaced apart laterally one from another so as to at least partially define longitudinal ports between successive riffles, the said riffles having their upper edges spaced apart from the said back for the purpose of defining, at least partially, a chamber between the said back and the said upper edges, and the said riffles having sides which are fluted so as to constitute peaks and valleys transversely of the said longitudinal ports, thereby defining, at least partially, air conduits leading into the space between the upper edges of the riffles and the said back.
